CLAIM

The ornamental design for a shoe rack, as shown and described.

DESCRIPTION

FIG. 1 is a front and left side perspective view of a shoe rack showing my new design;

FIG. 2 is a front elevational view;

FIG. 3 is a top plan view;

FIG. 4 is a right side elevational view, the left side being a mirror image thereof;

FIG. 5 is a rear elevational view; and

FIG. 6 is a bottom plan view thereof.

FIGS. 2-6 have been shown on and enlarged scale with respect to FIG. 1.

FIG. 1

FIG. 4

FIG. 2

FIG. 3

FIG. 5

FIG. 6
